UNITED STATES PATENT OFFICE

150,690

DESIGN FOR A VACUUM CLEANER

Gordon W. Florian, Bridgeport, Conn., assignor
to Air-Way Electric Appliance Corporation, To-
ledo, Ohio, a corporation of Delaware

Application May 25, 1948, Serial No. 146,560

Term of patent 14 years

(Cl. D9—2)

To all whom it may concern:

Be it known that I, Gordon W. Florian, a citizen of the United States and a resident of Bridgeport, Connecticut, have invented a new, original, and ornamental Design for a Vacuum Cleaner, of which the following is a specification, reference being had to the accompanying drawing, forming a part thereof.

In the drawing:

Figure 1 is a front elevational view of the vacuum cleaner with the same in upright position of use, showing my new design;

Figure 2 is a rear elevational view of the vacuum cleaner;

Figure 3 is a perspective view of the vacuum cleaner showing the same in horizontally disposed position of use; and

Figure 4 is an end elevational view of the vacuum cleaner.

I claim:

The ornamental design for a vacuum cleaner, as shown.

GORDON W. FLORIAN.
